[57] CLAIM

The ornamental design for a hinge joint for frame of rollable cart, as shown and described.

DESCRIPTION

FIG. 1 is a perspective view of a hinge joint for frame of rollable cart showing our new design;
FIG. 2 is a front elevational view thereof;
FIG. 3 is a rear elevational view thereof;
FIG. 4 is a top plan view thereof;
FIG. 5 is a right side elevational view thereof;
FIG. 6 is a left side elevational view thereof; and,
FIG. 7 is a front perspective view in use thereof, the broken line showing of the frame members is for illustrative purposes only and forms no part of the claimed design.
